DESIGN FOR A SLIP

Seamon Wolf, New York, N. Y.

Application January 16, 1941, Serial No. 98,114

Term of patent 3½ years

To all whom it may concern:

Be it known that I, Seamon Wolf, a citizen of the United States of America, residing in New York city, county of New York and State of New York, have invented a new, original, and ornamental Design for a Slip, of which the following is a specification, reference being had to the accompanying drawing, forming part thereof, wherein,

Figure 1 is a front view of a slip showing my new design.

Figure 2 is a rear view of the slip shown in Figure 1, and

Figure 3 is a fragmentary front view of one of the bust sections drawn on an enlarged scale.

The characteristic feature of my design resides in the combination on the specific slip disclosed, of the specific lace and embroidery trim on the bust section in association with the specific lace edging on the top, surplice front and bottom thereof, as shown.

I claim:

The ornamental design for a slip, substantially as shown and described.

SEMON WOLF.
